INVENTOR

BY Drake & Co., ATTYS.

UNITED STATES PATENT OFFICE.

LEOPOLD S. SAMUEL, OF NEWARK, NEW JERSEY.

SOAP CAKE.

SPECIFICATION forming part of Letters Patent No. 555,663, dated March 3, 1896.
Application filed November 27, 1895. Serial No. 570,315. (No specimens.)

To all whom it may concern:

Be it known that I, LEOPOLD S. SAMUEL, a citizen of the United States, residing at Newark, in the county of Essex and State of New Jersey, have invented certain new and useful Improvements in Soap Cakes; and I do hereby declare the following to be a full, clear, and exact description of the invention, such as will enable others skilled in the art to which it applies to make and use the same, reference being had to the accompanying drawings, and to letters of reference marked thereon, which form a part of this specification.

This invention relates to that class of soap cakes referred to more particularly in my prior patent, No. 549,687, in which each cake comprises two or more sections of different varieties of soap or saponaceous matter united permanently by wax or cementitious matter.

The particular object of this invention is to secure a more rigid union of the sections.

The invention consists in the improved soap cake and in the arrangements and combinations of parts, all substantially as will be hereinafter set forth and finally embraced in the clauses of the claim.

Referring to the accompanying drawings, in which like letters indicate corresponding parts in each of the figures, Figure 1 is a section of the soap cake in one of its forms. Fig. 2 is an inside view of one of the sections thereof, and Fig. 3 is a detail showing a roughened surface which may be employed.

In said drawings, *a* is the female and *b* the male member of the soap cake, and *c* is a cementitious or combining substance adapted to unite the said sections when employed with certain co-operating constructions hereinafter referred to. The said uniting substance is preferably of wax. The variety of wax preferred is cerosine.

In the preferred construction I form in the female section a shallow depression, as shown in Fig. 1, the side walls of which are undercut or reversely dovetailed, as at *e*. The male section is provided with a dovetailed projection *d*, conforming more or less closely to the recess or depression in plan and extending into the shallow recess, the lateral edges being correspondingly undercut. Into the shallow

depression, in the operation of uniting the sections, I pour liquid wax or cerosine and then press the projection of the male member into the said recess. By this operation the wax is forced outward to some extent and into the joint formed between the sections, forming, when solid, what may be termed a "key" or "feather" between the undercut surfaces, which acts to firmly unite the parts.

By means of the undercut surfaces and key or feather referred to the soap sections are held together firmly even though the key may have little or no adhesive affinity for the soap.

I may, in addition to the large recess and projection, as shown, roughen the surface of the soap cake, or form small indentations, scratches, and the like, so that when the liquid or fluid cerosine is forced out of the recess it will enter the recesses and interstices of the roughened surfaces, and thus more thoroughly and perfectly unite the parts.

Having thus described the invention, what I claim as new is—

1. The improved soap cake herein described, in which are combined saponaceous sections *a*, *b*, having undercut surfaces and a solidifiable fluid hardened within the recesses formed by said undercut surfaces and locking said sections together, substantially as set forth.

2. The improved soap cake herein described, in which are combined a plurality of different saponaceous sections *a*, *b*, having male and female parts held together by a key substance, the contiguous surfaces of said sections *a*, *b*, being roughened by indentations, scratches, or the like, whereby the key substance will more perfectly unite the parts, substantially as set forth.

3. The improved soap cake herein described, in which are combined a plurality of different saponaceous sections *a*, *b*, having undercut male and female parts projecting one into the other, and a solidified key substance, substantially as set forth.

4. The improved soap cake herein described, in which are combined a plurality of different saponaceous sections *a*, *b*, having undercut parts, and a non-hygroscopic substance adapted to be pressed into conformity to the surface of the sections and serve as a key for

holding said parts together, substantially as set forth.

5. The improved soap cake herein described, in which are combined a plurality of soapaceous sections *a*, *b*, having undercut surfaces of a binding wax underlying said undercut surfaces, substantially as set forth.

In testimony that I claim the foregoing I have hereunto set my hand this 25th day of November, 1895.

LEOPOLD S. SAMUEL.

Witnesses:

CHARLES H. PELL,
C. B. PITNEY.
